ELECTRONIC SQUARING CIRCUIT

France B. Berger, Watertown, Mass., and William A. Higinbotham, Santa Fe, N. Mex., assignors, by mesne assignments, to the United States of America as represented by the Secretary of War.

Application October 30, 1944, Serial No. 561,021

3 Claims. (Cl. 250—27)

1

This invention relates to electrical means for producing an output voltage or current which is a given function of an input voltage or current, and it relates more particularly to electrical means whose output varies as the square of the input.

In the rapid development of the electronic field, it has frequently been found necessary to produce a voltage or current that varies as some particular mathematical function, as, for example, a squared function, which is of the parabolic form. The present invention relates to electrical means for producing an output voltage or current of the latter variety.

One object of this invention is to provide as an output from a circuit, a voltage whose magnitude varies proportionally as the square of a variable input voltage.

Another object of the present invention is to have the output of this circuit respond practically simultaneously with any changes in the input, which is of particular value in connection with sweep circuits of cathode ray tubes.

Still another object of the present invention is to provide a simple, yet highly accurate and reliable, circuit to achieve the above-mentioned objects.

The above and other objects in view will appear more fully from the following detailed description, accompanying drawings and appended claims.

Referring now to the drawing wherein:

Fig. 1 is a simplified diagram of one specific embodiment of the present invention;

Fig. 2 is a graph showing variation of plate current (i_p) vs. grid voltage (e_g) for each of the tubes shown in the diagram of Fig. 1, with the sum of the plate currents being represented by the dashed curve;

Fig. 3 represents a schematic diagram of an illustrative embodiment of the present invention for which Fig. 1 is the simplified version thereof; and

Fig. 4 is a schematic diagram illustrating modified connections of Fig. 3.

It is to be understood that the circuit represented generally by Fig. 1 and more specifically by Fig. 3 may be referred to as a "squaring" circuit.

Referring now to Fig. 1, the input signal to the

2 squaring circuit is applied between terminal 5 and grounded terminal 6. The input may then be fed through biasing means 7 to control grid 8 of vacuum tube 9. At the same time, the input 5 may be fed through a phase inverter 10, the output being a voltage substantially the same as that applied to control grid 8 of vacuum tube 9 but being 180° out of phase therewith. This voltage may then be fed through biasing means 11 to control grid 12 of vacuum tube 13. Voltages appearing on control grid 8 of vacuum tube 9 and control grid 12 of vacuum tube 13 are then substantially equal but of opposite polarity. Cathode 15 of vacuum tube 9 and cathode 16 of 15 vacuum tube 13 may be connected to ground, and anode 17 of vacuum tube 9 and anode 18 of vacuum tube 13 may be connected together and thence through a common load impedance 20 to a source of B+ potential 21. The cathodes and anodes of tubes 9 and 13 are thus connected in a common cathode-anode circuit.

The general expression for plate current in a vacuum tube may be expressed as

$$25 a + bx + cx^2 + dx^3 \dots$$

where x is the voltage applied to the control grid, where a , b , c and d depend upon the particular characteristics of the vacuum tube. If the tubes are operated entirely within the negative grid

30 voltage region, fourth and higher powers of this series may be neglected. The general expression for plate current in vacuum tube 13 may be expressed as $a - bx + cx^2 - dx^3 + \dots$, the change in sign of x being due to the fact that the voltage appearing at control grid 12 of vacuum tube 13, although similar to that applied to control grid 8 of vacuum tube 9, is of opposite polarity.

The plate currents for vacuum tube 9 and vacuum tube 13 will flow through common load impedance 20. By addition of the two expressions for plate current, and neglecting terms above the third power, it will be seen that the odd power terms cancel out, leaving the resultant expression $2a + 2cx^2 + \dots$, $2a$ being a constant which 40 can be eliminated by suitable level-setting action and $2c$ being a proportionality factor which can be altered, if desired, by suitable amplification or attenuation. Since the voltage output in question is that produced by the flow of the 45 plate currents of vacuum tubes 9 and 13 through

50 plate currents of vacuum tubes 9 and 13 through

load impedance 20, the voltage output will vary as the term x^2 , thus providing the "squaring" feature of the present invention.

A graphical representation of the plate currents for vacuum tubes 9 and 13 is given in Fig. 2. The curve i_{p_1} may represent the mutual characteristic curve of vacuum tube 9, and is plotted in the normal sense where the origin of the curve is at the lower right-hand corner and the plate current i_{p_1} increases with an increase of grid voltage e_{g_1} to the right. The curve i_{p_2} similarly may represent the plate current of vacuum tube 13, and is drawn to the same ordinate scale as curve i_{p_1} but with the abscissa in the opposite direction, that is to say plate current i_{p_2} increases as grid voltage e_{g_2} increases to the left, the origin of this curve being at the lower left-hand corner. The dashed curve shown in Fig. 2, obtained by adding the ordinates of i_{p_1} and i_{p_2} and thus representing the resultant plate current through load impedance 20, is very nearly that of a parabola, or in other words, varies as a squared function.

The characteristic curves shown in Fig. 2 are merely representative of plate current vs. grid voltage curves, and may typify the operation of various types of vacuum tubes. For ease of description, certain voltages which may be realized in actual operation have been indicated directly on these curves. These are not to be construed as required voltages to be applied to the circuit, but merely represent values that have been found suitable in one illustrative embodiment of the present invention (Fig. 3), wherein 6B8 type vacuum tubes are used in place of vacuum tubes 9 and 13 of Fig. 1. The 6B8 type tube was found to have particularly suitable characteristics for the purposes of the present invention, due in large measure to the high second harmonic distortion produced by tubes of that type. Other tubes having similar characteristics might also be used for this purpose.

Referring now to Fig. 2, it will be noted that the characteristic curves of plate current vs. grid voltage intersect at point 22, which is hereinafter referred to as the crossover point. This point will generally, because of the symmetry of the figure, intersect the grid voltage axis half way between the origins of the two graphs. The crossover point represents the value of grid voltage at which the resulting plate current flowing through load impedance 20 of Fig. 1 will be at its minimum. This therefore may represent the point at which the signal input at terminal 5 of Fig. 1 is zero. If then the signal applied to terminal 5 is increased in a positive direction, the plate current i_{p_1} of vacuum tube 9 will increase, and at the same time, plate current i_{p_2} of vacuum tube 13 will decrease. If, however, the signal applied to terminal 5 is increased in a negative direction, the plate current i_{p_2} of vacuum tube 13 will increase and at the same time plate current i_{p_1} of vacuum tube 9 will decrease. As previously mentioned, the opposite actions of vacuum tubes 9 and 13 are due to the fact that the signals appearing on the control grids of these tubes are of opposite polarity. The resultant current flowing through load impedance 20 of Fig. 1 is the sum of i_{p_1} and i_{p_2} , and is represented by the dotted curve of Fig. 2 which is substantially parabolic in form.

Any change in the input signal on terminal 5, from the value corresponding to the crossover point, will produce a change in the voltage across load impedance 20 proportional to the square of

the change in the input signal. Thus the input signal applied to terminal 5 may be either negative-going or positive-going. It is preferable for the input signal to begin at a value corresponding to the crossover point, said point coinciding with minimum current flow through load impedance 20 and hence maximum voltage output.

Referring now to the embodiment shown in Fig. 3, vacuum tubes 30 and 31 thereof correspond to vacuum tubes 9 and 13 of the simplified version shown in Fig. 1. The particular tubes 30 and 31 may be pentodes of the 6B8 type, it being understood, of course, that other tubes having similar characteristics may be used. Vacuum tube 32 acts as an amplifier and phase inverter. Vacuum tube 33 also acts as an amplifier wherein the signal input is applied to cathode 41, the output at anode 50 being of the same phase as the input to cathode 41. Tubes 32 and 33 together provide essentially the phase-inverting action required of the inverter 19 shown in Fig. 1. The type of tubes which may be used here is not particularly critical, but may be of the medium mu variety, such as a 6SN7, or of the high mu variety, such as the 6SL7. Inasmuch as these particular tube types have two triode elements in a single envelope, they are particularly suitable for use in the present invention.

When the signal input is applied to terminal 34 a voltage, which is developed across grid leak resistor 35 connected to ground, is applied to control grid 36 of vacuum tube 32. One voltage output is developed across anode load resistor 51 and is applied directly to control grid 38 of vacuum tube 30, and a second output is developed across variable cathode load resistor 42 and is applied directly to cathode 41 of vacuum tube 33. Variable cathode resistor 42 has one side connected to cathodes 40 and 41 of vacuum tubes 32 and 33, and the other side connected to a negative voltage bias source 43, the positive side of the latter being connected to ground.

By means of variable resistance 42, the voltage drop across load resistance 60 may be adjusted in order to obtain the desired initial voltage output at junction 61. This variable resistance may be one of the conventional type or may be a pentode-type vacuum tube having the advantage of substantially constant current flow.

The potential of control grid 44 of vacuum tube 33 may be varied positively or negatively with respect to ground by means of potentiometer 45, the arm of which is connected to said grid. One side of potentiometer 45 is connected to the positive terminal of biasing means 46, the negative terminal being connected to ground. The other side of potentiometer 45 is connected to the negative terminal of biasing means 47, the positive terminal being connected to ground. The thus-achieved variation of potential on control grid 44 serves in effect relatively to shift the characteristic curves of the pentodes, thus providing means for centering the resultant dashed parabolic curve of Fig. 2 about a desired initial voltage. This will also permit adjustment for any minor variations incurred should vacuum tubes have to be changed.

Anode 37 of vacuum tube 32 and anode 50 of vacuum tube 33 may be connected to a suitable source of positive potential 62 through load resistors 51 and 52, respectively. Screen grids 63 and 64 of vacuum tubes 30 and 31 may be connected together and thence connected directly to a source of positive potential which, in the

embodiment shown in Fig. 3, is potential source 62.

The signals issuing from anode 50 of vacuum tube 33 and anode 37 of vacuum tube 32 are 180° out of phase with respect to each other. The signal issuing from anode 37 may be fed directly to control grid 38 of vacuum tube 30, and the signal issuing from anode 50 may be fed directly to control grid 53 of vacuum tube 31. Due to the fact that the outputs at the anodes of vacuum tubes 32 and 33 are coupled directly to vacuum tubes 30 and 31, respectively, the latter are operated at a higher voltage level than vacuum tubes 32 and 33. For this reason, in the embodiment shown, cathodes 55 and 56 of vacuum tubes 30 and 31 are connected together and thence to a source of positive potential 67.

An advantage of the direct coupling between tubes 33 and 31, and between 32 and 30, is that objectionable time constants are obviated thereby, thus enabling the circuit to respond almost instantaneously to changes in the original input on terminal 34.

Suppressor grids 65 and 66 of vacuum tubes 30 and 31 may be connected to their respective cathodes 55 and 56. Anodes 57 and 58 of vacuum tubes 30 and 31, respectively, are also connected together and thence to a source of B potential 69 through load resistance 60. The plate currents of vacuum tubes 30 and 31 are combined in load resistance 60, the resultant current varying as the square of the input signal to terminal 34. However, the voltage drop across load resistance 60 varies negatively as the square of the input to terminal 34. The output of the foregoing squaring circuit may be taken directly from the anodes 57 and 58 at junction 61.

If vacuum tubes 32 and 33 are either 6SN7's or 6SL7's and vacuum tubes 30 and 31 are 6B8's, the following voltages have been found to be quite suitable in the embodiment shown in Fig. 3. Voltage source 43, which provides negative bias for cathodes 49 and 41 of vacuum tubes 32 and 33, respectively, may be approximately 150 volts. Positive potential source 62 may be approximately 200 volts, and positive potential source 69 may be approximately 350 volts, and positive potential source 67, which supplies bias for cathodes 55 and 56, may be approximately 100 volts.

If 6B8's are used, the crossover point (Fig. 2) will occur at a grid voltage of approximately -12 volts. This means that when the signal input to the squaring circuit is zero, variable resistance 42 can be adjusted so that control grids 38 and 53 of vacuum tubes 30 and 31, respectively, are about 12 volts below the potential of their cathodes 55 and 56.

Under these conditions the resultant current (represented by the dashed curve of Fig. 2) will remain substantially parabolic for a signal input variation of about 16 volts.

The voltage output from junction point 61 of Fig. 3, which varies negatively as the square of the input voltage to terminal 34, therefore varies with respect to the relatively high D.-C. potential at junction point 61 by a factor proportional to the square of the signal input voltage. It may be desirable, however, to obtain a voltage which varies from ground potential by the aforesaid factor. This may be accomplished by the use of a relatively simple level-setting circuit, which is indicated by the dashed portion of Fig. 3. This circuit is usually referred to as a "D.-C. restorer"

or "clamping circuit," and is well known in the art.

The D.-C. restorer or clamping circuit may comprise condenser 71, resistor 72, vacuum tube 73, and output terminals 74 and 75. For general operation, the time constant determined by the values of condenser 71 and resistor 72 should be large as compared to the period of the input voltage to terminal 34. The voltage output of the D.-C. restorer or clamping circuit is taken from anode 76 of vacuum tube 73 and varies negatively with respect to ground as the square of the voltage applied to terminal 34.

Although the discussion of the basic operation of the circuit of Fig. 1 indicated that the variable input is applied to the grids of vacuum tubes 9 and 13, if desired, in other embodiments the input may be applied to the cathodes and the grids connected to ground as illustrated in Fig. 4. The connections in Fig. 4 are identical to those illustrated in Fig. 3, except that the cathodes 55 and 56 of the pentodes 30 and 31 are now connected to the plates of the triodes 32 and 33 and the control grids 38 and 53 are grounded through a biasing battery 67-a, the latter corresponding in its function to the biasing battery 67 in Fig. 3.

Although separate vacuum tubes have been shown in the drawings, it is to be understood that, if desired, their electrodes may be placed inside a single envelope as in a multi-purpose tube.

One specific application of the present invention is shown in copending application of Luis W. Alvarez, Serial No. 542,287, filed June 27, 1944, wherein it was desired to obtain a voltage that varied directly as the square of another voltage. Other applications of the invention may be made in electrical calculating or computing machines wherein representation of squared term functions are needed. These and other applications of the present invention will readily occur to those skilled in the art.

Having thus described the invention, what is hereby claimed as new and desired to be protected by Letters Patent is:

1. A squaring circuit including vacuum tube means having a plate circuit, a grid circuit and a cathode circuit, at least one of the latter two circuits including two separate electrode elements, means for applying substantially similar input signals of opposite polarity to said electrode elements, and a load impedance in the plate circuit, the output developed across said load impedance being substantially proportional to the square of the input.

2. A squaring circuit including vacuum tube means having two separate control grids and a common cathode-anode circuit, means for applying an input signal to one of said control grids, inversion means for producing a substantially similar signal to opposite polarity, means for applying said latter signal to the other one of said control grids, and a load impedance in the cathode-anode circuit, the output developed across said load impedance being substantially proportional to the square of the input.

3. A squaring circuit including a pair of vacuum tubes each containing at least a cathode, an anode and a control grid, a common anode-cathode circuit for said tubes, another vacuum tube containing a cathode, an anode and a control grid and having anode and cathode load impedances, means for applying an input signal to the control grid of said last-mentioned tube,

thereby developing signals of opposite polarity across said impedances, means for applying the signal developed across the anode load impedance to the control grid of one of the tubes of said first-mentioned pair of tubes, and means for applying the signal developed across the cathode load impedance to the control grid of the other tube of said pair of tubes, said grid-applied signals of opposite polarity being substantially similar, and a load impedance in the common-anode-cathode circuit of said first-mentioned pair of tubes, the output being developed across said last-mentioned load impedance and being sub-

stantially proportional to the square of the input signal.
